228,321

SNACK FOOD PRODUCT OR THE LIKE

Richard M. Vondel and Clarence H. Soderlund, Battle Creek Township, Mich., and Ralph A. Maldari, Brooklyn, N.Y., assignors to Kellogg Company, Battle Creek, Mich.

Filed Sept. 18, 1972, Ser. No. 289,596

Term of patent 14 years

Int. Cl. D1—01

U.S. Cl. D1—1

FIG. 1 is a plan view of a snack food product or the like showing our new design, the view depicting the top or the bottom thereof as both are the same;

FIG. 2 is a side view thereof, the view from all sides being the same; and

FIG. 3 is a cross-section thereof taken on line 3—3 of FIG. 1.

We claim:

The ornamental design for a snack food product or the like, substantially as shown and described.

References Cited

UNITED STATES PATENTS

D. 180,900	9/1957	Gilmore	-----	D1—01
D. 207,699	5/1967	Scharschmidt	-----	D1—01
D. 213,945	4/1969	Cooper	-----	D1—01

OTHER REFERENCES

Washington Post "Potomac" Mag., Nov. 24, 1968, p. 10, cookie item.

JOEL STEARMAN, Primary Examiner

L. J. PERLSTEIN, Assistant Examiner